UNITED STATES PATENT OFFICE.

CHARLES M. DELANY, OF GREEN BAY, WISCONSIN, ASSIGNOR TO ECONOMY TOOL MANUFACTURING COMPANY, OF GREEN BAY, WISCONSIN.

TOOL HOLDER.

Application filed June 11, 1925. Serial No. 36,358.

The invention relates to a tool holder, especially designed for holding cutting tools.

The primary object of the invention is the provision of a holder of this character, wherein the body thereof is provided with a channel in which is received the desired tool, which latter is held in its position by a clamping plate, the same being of novel construction and mounted on the body of the holder to maintain rigidity to said clamping plate.

Another object of the invention is the provision of a holder of this character, wherein the construction thereof is novel, so that a tool when held therein can be readily and easily adjusted, and likewise the manner of clamping the tool in said holder is novel, to assure the firm and secure clamping of said tool, when in use with the holder.

A further object of the invention is the provision of a holder of this character, which is extremely simple in construction, thoroughly reliable and efficient in its purpose, enabling the tool to be quickly adjusted, and when set in said holder will be firmly and securely fastened, strong, durable, and inexpensive to manufacture.

With these and other objects in view the invention consists in the features of construction, combination and arrangement of parts, as will be hereinafter fully described, illustrated in the accompanying drawings, and pointed out in the claim hereunto appended.

It is to be understood, however, that changes, variations and modifications may be made in the invention, such as come properly within the scope of the appended claim, without departing from the spirit of the invention or sacrificing any of the advantages thereof.

In the accompanying drawing:

Figure 1, is a side elevation of a tool holder constructed in accordance with the invention.

Figure 2, is an edge elevation thereof.

Figure 3, is an end view of the same.

Figure 4, is a sectional view taken on the line 4—4 of Figure 1, looking in the directions of the arrows.

Similar reference characters indicate corresponding parts throughout the several views in the drawing.

Referring to the drawing in detail, A, designates generally the body of the tool holder, which is of uniform thickness and

width throughout its length, one end of said body being beveled as at 5, while the opposite end is reversely beveled as 6, and at one corner is a lateral extension 7, which is for a purpose presently described.

Formed in one side face of the body A, and disposed diagonally thereof is a tool channel or groove 8, which opens through opposite reversely beveled ends of said body, this groove being of the same depth and width throughout the extent thereof, and in which is adapted to seat the tool to be used in the holder.

In the other side face of the body A, of the holder at the working end thereof is formed a circular bolt opening 9, in which is received the bolt 10, the head 11, which is held in a counter-sink 12, therefor, while the bolt 10, is provided with a squared transverse passage 13, registering with the channel or groove 8, but of slightly greater size than the same, so that a tool will freely pass through the passage 13, to be engaged in the said channel or groove for the seating of the tool therein.

The outer end of the bolt 10, is reduced at 14, and threaded at 15, to receive a nut 16, tapped thereon. The head 11, of the bolt in its edge is formed with a notch and likewise the wall of the counter-sink 12, is provided with a notch to accommodate a locking pin 17, deposited in the notches 18, in the respective head and counter-sink, and in this manner the bolt is held against rotating movement when the nut 16, is tightened or loosened on the same.

Engaged about the reduced portion of the bolt 10, is a clamping plate 18', which is formed with a flanged or ribbed end or edge 19, adapted to fit within a groove 20, formed in channeled face of the body A, at one side of said channel or groove 8, the lateral extension 7, being for the purpose of accommodating said groove 20, which is disposed angularly with respect to the groove 8 or channel 8, as will be obvious. The flange or rib engagement in the groove 20, prevents the clamping plate from turning on the bolt 10, the plate 18', being formed with a recess 21, for the larger portion of said bolt, and this plate worked downwardly by the nut 16, toward the body A, of the holder to firmly secure the tool in its adjusted position in the channel or groove 8, in said body.

The working end of the body A, of the

holder flush with one side wall of the channel or groove 8, therein is provided with a projection 22, which backs up the protruding portion of the tool beyond said 5 working end of the holder.

The flanged or ribbed edge 19, of the clamping plate 18', give rigidity to the latter, as will be apparent. The tool holder and the tool when placed therein is used in the 10 ordinary well known manner.

What is claimed is:

A tool holder of the kind described, comprising a member of uniform width and thickness having reversely beveled ends, a 15 lateral extension at one end of the member, said member having a channel diagonally disposed throughout one face thereof and opening through the reversely beveled ends, said member further having a bolt-hole cen-

tered relative to the channel and opening through the same next to the extension, a headed bolt in the hole and having its head countersunk in the hole, said bolt having a squared opening aligning with the channel and of greater size than the latter, means holding the bolt against turning movement, a clamping plate surrounding the bolt and having a side rib countersunk in the extension, the rib and countersink therefor being at an acute angle to the channel, a nut on the bolt and working against the plate, and a projection on the member flush with the side of the channel remote from the extension to back up a tool when within said channel. 20 25 30 35

In testimony whereof I affix my signature.

CHARLES M. DELANY.
